SAFETY RAZOR BLADE HONER

Frank E. Housh, Miami Beach, Fla.

Application August 29, 1932, Serial No. 630,934

7 Claims. (Cl. 51—211)

The object of the invention is to provide a hone for safety razor blades and the like which will make possible the more or less automatic honing or sharpening of the blade in that the invention is designed to receive the blade and thereafter to be vibrated by the operator without the exercise of care or attention on his part; to provide a hone consisting of separable elements which may be separated and the honing operation carried out by the use of the fingers when desired by moving the blade being operated upon back and forth across the hone; and generally to provide a device of the kind indicated which is of simple form and susceptible of cheap manufacture.

With this object in view, the invention consists in a construction and combination of parts of which a preferred embodiment is illustrated in the accompanying drawing but to which embodiment the invention is not to be restricted. Continued use in practice may dictate certain changes or alterations and the right is claimed to make any which fall within the scope of the annexed claims.

In the drawing: Figure 1 is a perspective view of a device constructed in accordance with the invention.

Figure 2 is a sectional view on the plane indicated by the line 2—2 of Figure 3.

Figure 3 is a central horizontal sectional view of the structure shown in Figure 1.

Figure 4 is a sectional view on the plane indicated by the line 4—4 of Figure 3.

Figure 5 is a sectional view similar to Figure 2 but showing a modified form of the invention in which the honing surfaces are duplicated.

Figure 6 is a view similar to Figure 2 but of still another modification.

Figure 7 is a perspective view of one of the elements or sections of still another modified form of the invention.

Figure 8 is a central longitudinal vertical sectional view of the invention constructed in accordance with the form illustrated in Figure 7 but showing the two sections connected.

Figure 9 is a sectional view on the plane indicated by the line 9—9 of Figure 8.

The invention comprises a construction wherein concave honing surfaces are disposed in facing relation, so that the blade may be placed between the two and the device oscillated or shaken by hand to move the blade back and forth over the surfaces, whereby sharpening of the edges is effected, since the blade will lie with only its edges in contact with the honing surfaces and may

not be turned over with respect to the surfaces because the two surfaces jointly define a space cross-sectionally oval, the minor axis of the oval being shorter than the width of the conventional razor blade and the major axis being greater than the width of such a blade. In that form of the invention illustrated in Figures 1 to 4 inclusive, the honing surfaces are formed in blocks 10 of abrasive or polishing material, these blocks being housed in a casing 11 of which the side walls 12 are ribbed throughout their length on a vertical center line, as indicated at 14, the edges of the blocks 10 at the side edges of the concave surfaces resting on these ribs which provide seats or shoulders and maintain a spaced relation of the blocks. The casing 10 is designed to fit the enclosed blocks snugly, so that there may be no relative movement between them and it.

One end wall of the casing is formed with an entrance opening 15 in the form of a slot through which a blade, such as indicated at 16, may be readily passed. The slot or entrance opening 15 is removably closed with a gate 17, pivotally mounted on the end wall of the casing 11 as indicated at 18, the pivot holding the gate 17 close enough to the wall of the casing to prevent free pivotal movement, so that the gate is swung from its open to its closed position and vice versa against the friction interposed by the contact of the gate with the casing.

In the use of the device, the blade is inserted through the opening or slot 15 after shifting the gate 17 from obstructing position with reference to the slot, and thereafter the gate is closed and the blade 16 is enclosed by the device, when the casing may be moved back and forth in the hand and inverted periodically, the blade, during these movements, sliding back and forth over the concave faces of the blocks 16 and by reason of its edges alone contacting with these concave faces, the edge is given a fine degree of keenness.

To provide for the sharpening or honing operation being performed mainly at the centers of the blocks 10, the concave surfaces of the two blocks longitudinally are arranged on converging lines toward the longitudinal center of the blocks, thus leaving a peak or ridged portion 19 at the horizontal center. By this arrangement, if the blade be not perfectly flat, as is frequently the case, any slight deviation from flatness will not interfere with the effective honing, since the peak portion 19 will at some time or other engage every point on the edge of the blade as it is moved back and forth by the oscillation of the container.

In the construction shown in Figure 5, the same

idea is carried into effect as in Figures 1 to 4, but the casing 11^a in this instance is of a greater depth than the casing 11, so that it may house three blocks, such as indicated at 10^a and 10^b, the latter block being disposed between the two former and being concave on opposite faces, so that it has one concave face facing the concave face of each of the others. The blocks 10^a and 10^b are spaced through the instrumentality of the ribs 14^a, in the same manner as the blocks 10 are spaced. This construction provides for sharpening more than one blade at a time, as the compartments provided by the spaced adjacent blocks are each adapted to receive a blade. Thus when the device is in the multiple form shown in Figure 5, a blade may be sharpened in each compartment defined by the honing surfaces, by oscillating the device as a whole in the same manner as described with reference to the construction shown in Figure 1.

In the modification shown in Figure 6, the construction is such as to make possible the honing of cross-sectionally arcuate blades, such as shown at 20. In order that the edges of the blade 20 may engage a honing surface on the concave side, a cross-sectionally arcuate plate 21 is employed to be used in conjunction with a second cross-sectionally arcuate plate 22. Both the plates 21 and 22 are of a material to effectively produce a keen edge on the blade being operated upon and they are supported in spaced relation in the casing 23, having an access opening to the space between them, such access opening being formed in the end of the case in the same manner as described with reference to Figure 1. To support the plate members 21 and 22 in the desired spaced relation, their side edges are seated in rabbets 24 formed in the interior face of the side walls of the case 23. The plate 21 is formed to a greater radius than the radius of the blade 20, while the plate 22 is formed on a less radius than that of the blade 20. Thus, whether the blade contacts with the outer surface of the plate 21 or the inner surface of the plate 22, its side edges will be brought into contact with the same and they will be honed and sharpened, as the case 23 is moved back and forth.

That form of the invention illustrated in Figures 7 to 9 contemplates the use of a case 26 which consists of the complementary sections 26^a and 26^b which are identical in form and which may be coupled together by means of pin and socket connections, the pins 27 on one section entering the sockets 28 on the other.

Each of the casing sections carries a cross-sectionally arcuate plate 29 supported in the side wall of the section by means of lateral lips 30 which enter rabbets formed in the side wall. When the two casing sections are connected together, therefore, the plates 29 are disposed with their concave sides in facing relation to function in the same manner as the blocks 20 when the casing is vibrated or shaken by the hand. An access slot and a closure gate are unnecessary in this form since the casing sections are separate, and a blade is disposed on the honing surfaces by separating the sections and placing the blade in the one and reconnecting the sections. The plates 29 may be of any suitable material. If they are abrasive, a bead is formed across them at their longitudinal centers, as shown at 31 and functions as the real honing medium, as the blade must move over this bead in being shifted from one end of the casing to the other.

If the plates 29 be metallic, as they may be,

the element 31 may be a hardened steel strip laid into close contact with the concave surfaces at the center. This strip may be roughened at its edges so that as the blade is moved back and forth it functions to reduce the edges of the blade to a condition of fine keenness.

The plates 29 in length are less than twice the length of the blades to be sharpened, so that the blade being operated upon may have one end abutting the end wall of the case without the other end passing off the bead or strip 31.

In the form of the invention shown in Figure 7, the two sections 26^a and 26^b may be separated and either or both used as a hone for sharpening blades by moving them back and forth with the fingers. The two sections may be used simultaneously under the two hands of the operator and with two different blades.

By separating the honing surfaces, as shown, it is impossible for the edge of the blade being sharpened to be brought edge on against either surface, when it is moving in a position adjacent the side wall of the casing, or if the case be turned over laterally, as in such instances it will strike the soft material of the case and not the hard surface of the opposite honing element.

The invention having been described, what is claimed as new and useful is:

1. A safety razor blade honer comprising concave honing members disposed with their concave surfaces in spaced relation and defining a cross-sectionally oval space of which the minor axis is less than the width of the conventional safety razor blade and the major axis is greater than the width of such blade, and a housing enclosing the honing members and formed with an opening to admit a razor blade between them to be rubbed against such surfaces when the device as a whole is oscillated.

2. A safety razor blade honer comprising concave honing members disposed with their concave surfaces in spaced relation and defining a cross-sectionally oval space of which the minor axis is less than the width of the conventional safety razor blade and the major axis is greater than the width of such blade, a housing enclosing the honing members and formed with an opening to admit a razor blade between them to be rubbed against such surfaces when the device as a whole is oscillated, and spacers of non-abrasive material separating the honing members at their longitudinal edges.

3. A safety razor blade honer comprising concave honing members disposed with their concave surfaces in spaced relation and defining a cross-sectionally oval space of which the minor axis is less than the width of the conventional safety razor blade and the major axis is greater than the width of such blade, a housing enclosing the honing members and formed with an opening to admit a razor blade between them to be rubbed against such surfaces when the device as a whole is oscillated, and spacers of non-abrasive material separating the honing members at their longitudinal edges and consisting of longitudinal beads on the inner faces of the side walls of the casing.

4. A safety razor blade honer comprising concave honing members disposed with their concave surfaces in spaced relation and defining a cross-sectionally oval space of which the minor axis is less than the width of the conventional safety razor blade and the major axis is greater than the width of such blade, and a housing enclosing the honing members and formed with an opening to

5 admit a razor blade between them to be rubbed against such surfaces when the device as a whole is oscillated, the opposite honing surfaces being arranged on converging lines to provide peak portions at their longitudinal centers.

10 5. A safety razor blade honer comprising an element provided with facing concave honing surfaces defining a space of cross-sectionally oval contour of which the minor axis is less than the width of a conventional safety razor blade and the major axis greater than the width of such blade, whereby a blade may be inserted between the honing surfaces and moved over them for sharpening by the oscillation of said element.

15 6. A safety razor blade honing device comprising an element formed with spaced facing concave honing surfaces arranged on converging lines to form peaks at their longitudinal centers, said honing surfaces defining the top and bottom 20 walls of a cross-sectionally oval-shaped chamber for the reception of a safety razor blade to

be engaged by said surfaces and wiped over them by the oscillation of said element, the minor axis of said oval-shaped chamber being less than the width of a conventional safety razor blade and the major axis of said chamber being greater than the width of such blade.

25 7. A safety razor blade honer comprising a casing composed of complementary sections and means for securing the same in assembled relation, concave plates disposed one in each of the sections and having a transversely arranged bead on its concave face at its longitudinal center, said plates jointly defining the top and bottom walls of a cross-sectionally oval-shaped chamber whose minor axis is less than the width of a conventional safety razor blade and whose major axis is greater than the width of said blade, the length of said plates being less than twice the length of a conventional safety razor blade.
